UNITED STATES PATENT OFFICE

REMIGIO PERSICO, OF PITTSBURGH, PENNSYLVANIA

PARTIAL SELF-WINDING MECHANISM

Application filed January 21, 1929. Serial No. 234,013.

The present invention relates to partial self-winding mechanisms, which after the original winding of a series of springs, tend to rewind the prime-actuating springs, and to cause the whole mechanism to run quite a long period, without rewinding.

In the drawings, I have illustrated a complete embodiment of the invention, and in which,

19 Figure 1 is an end elevation of the device, shown in Figure 6, taken from the left thereof.

Figure 2, is a vertical section taken on line 2—2 of Figure 6.

15 Figure 3, is an enlarged detail of a rim-gear guide, taken on line 3—3 of Figure 1.

Figure 4, is an enlarged top view of a a brake device, used in connection with the rim-gear, and taken on line 4—4 of Figure 1.

20 Figure 5, is an end view of Figure 4.

Figure 6 is a side elevation of the whole mechanism.

Figure 7 is an end view of Figure 6, taken from the right thereof.

25 Figure 8 is a plan view of a clutch and associated parts, taken on line 8—8 of Figure 7.

Figure 9 is a front elevation of a saw-table and saw, belted to the front central shaft of the present invention.

30 Figure 10 is a partial side elevation of Figure 9, taken from the right side thereof.

In the drawings, the numerals 1, 2, 3, indicate supports, which are rigidly mounted in the base plate 4, by means of the socket castings 5, 6, 7 as shown.

35 Mounted in the supports 1, 2, 3 preferably in roller bearings, are a series of shafts 8, 9, 10 etc. which carry the planetary gears 11, 12, 13 etc. on one end thereof respectively, and on their opposite ends said shafts carry the "rewinding" gears 14, 15, 16 etc. As seen in Figure 1, the gears 11, 12, 13 engage the periphery of the rim-gear 17, and the internal teeth 18 of the latter engage the idler gears 19, 20, 21. The idler gears are each mounted on their respective shafts 22, 23, 24, carried by the support 1, and preferably by roller bearings therein.

40 The idler gears 19, 20, 21 engage the teeth 50 of the front central gear 25, mounted on the

central shaft 26, which shaft extends through the machine, having bearings in the supports 1, 2 and 3. It will be seen that the rim-gear 17 is supported in alignment by the three roller guides 27, 28 and 29, the details of which are shown in Figure 3 of the drawings, in which a base casting 30, is surmounted by the cap-casting 31 and both securely attached to the support 1, by means of the bolts 32, 32. The castings 30 and 31 are preferably split-castings, so that the rollers 33, 34 can be conveniently mounted in them as shown in Figure 3. The rollers 33, 34 engage the faces of the rim-gear 17, and it is evident that as the rim-gear is revolved by the planetary gears 11, 12, etc. the rollers will keep the rim-gear in vertical alignment with the actuating gears just named, and with the idler gears 19, 20 and 21.

55 It is evident that when the actuating gears 11, 12, 13 operate the rim-gear, and the central gear 25, (as will be explained hereinafter), that a brake may be necessary to control the speed of the machine. This is provided by the device shown in Figures 4 and 5 in which a 60 suitably padded lever 35, hinged at 36 to the casting 37, which last is mounted at 38 on the supporting wall 1. The amount of pressure exerted on the rim-gear 17 by the lever 35 is governed by means of the locking bar 39, 65 hingedly mounted on the support 1, as shown at 40, Figures 4 and 5. It will be seen that the locking-bar 39 is provided with a series of indentations 41, 41 which engage over the lever 35, whereby governing the intensity of 70 pressure exerted against the face of the rim-gear 17.

75 Referring to the Figure 2 of the drawings, it will be seen that on each of the shafts 8, 9, 10 are mounted coil-springs 42, 43, 44 respectively, the inner ends of which are each rigidly attached to the shafts, while the outer ends of said springs, are each attached to the pins 45, 45 etc. mounted in the support 2. It will also be seen that the shafts 8, 9, 10 etc. are each made up of two disconnected 80 portions, to wit, 46, 47; and that between these sections or parts there is inserted a clutch, 49. The teeth of clutch 49 are 85 preferably formed so that a clock-wise actuation 90

of portion 47 of shaft 8 for instance, will be transmitted through clutch 49 to the portion 43 of shaft 8, and thereby actuate gear 11. It will also be evident, that when the spring 42 is wound up, same will supply such actuation of shaft 8. The clutch 49 is spring-held as shown by the spring 51, and the two halves 52, and 53 of said clutch. From which description it is clear that when the spring 42 actuates portion 47 of shaft 8, that the portion 53 will actuate portion 52 of said clutch and thus turn portion 46 of the shaft. It is equally clear, that if portion 47 of shaft 8 is actuated in an anti-clockwise direction, as observed from the left in Figure 6, that the teeth 54, would merely "ride" on each other, and no motion would be transmitted to portion 46, nor gear 11. The purpose of this arrangement of parts will be more fully explained as the description proceeds.

It is seen from Figures 1, 6 and 7 of the drawings that when the front central gear 25 is actuated by means of the gears shown in Figure 1, and before explained, that such actuation will be transmitted through the shaft 26 to the rear central gear 55 mounted in the support 3. This gear is provided with teeth 56 on its peripheral face 57, and is adapted to transmit motion received through shaft 26, by means of said teeth to the rewinding gears 14, 15, 16 etc. These rewinding gears are loosely and revolvably mounted on section 47 of the shafts 8, 9, 10 etc. and it is evident that as portion 47 of the shaft last named revolves in a clockwise direction as seen from the left of Figure 6, by means of the actuation of the springs 42, 43, 44 etc. the gears 14, 15, 16 etc. will receive no motion from said shafts.

However as the rear central gear revolves in a clockwise direction, it is clear that the said gears 14, 15, 16 etc. being in mesh therewith will normally revolve in an anti-clockwise direction, but are incapable of transmitting said motion to the shafts 8, 9, 10 etc. unless acted on by the clutches 58, 58, as will now be explained. Each shaft 8, 9, 10, etc. is provided with a clutch 58, 58, etc. the right side of which 59 is slidable on the portion 47 of said shafts in a longitudinal direction as seen in Figure 6 of the drawings. The portion 60 on which the portion 59 rides is of an angular cross-section as shown in Figure 8, so that when the teeth of part 59 are operated in an anti-clockwise direction as observed from the left of Figure 6, the portion 60 of the shafts 8, 9, 10 will also be turned in an anti-clockwise direction, and as can be seen from an inspection of the teeth of clutch 49, when such a motion takes place in the portion 47 of the gear shafts, the teeth of clutch 49 merely "click" past each other, and do not interfere with the motion of the gears 11, 12, 13 etc. and heretofore mentioned in this specification.

It is seen in Figures 6 and 7 of the drawings that the part 59 of clutch 58, carries a grooved casting 61 rigidly mounted thereon which slides longitudinally with part 59 on the shaft end 60. In Figures 6, 7 and 8 there is shown an annular part or ring 62, which is mounted by means of the extensions 63, 63 etc. on the rear central gear 55, and revolves constantly with it. This ring 62 is in continuous engagement with the grooves 64 of the castings 61 as shown. The ring 62 has on its outer side a depressed portion 65, extending approximately from 66 to point 67 Figure 7; and on its inner face the ring 62 is provided with a bossed or raised portion 68 of substantially equal length to the depressed portion 65 just described.

From Figure 8 it is evident that as the ring 62 is revolved the part 59 of clutch 58 will be actuated along the shaft in a longitudinal direction, according to the position of the portion 69 of the ring, and the location of the bossed portion 68, in that when portion 68 engages the groove of the part 61, the portion 59 of the clutch will then be moved into engagement with the teeth of the part 70 of said clutch 58. When this action takes place it is evident that the anti-clockwise motion being constantly received by the gears 14, 15, 16 from the gear 57, will then be transmitted through means of the clutch 58 to the end 60 of the shafts 8, 9, 10 etc., and said shafts will then revolve in an anti-clockwise direction, and wind up the springs 42, 43, 44 etc.

From the Figure 7, it is seen that as gear 55 revolves the bossed portion 68 of the ring 62 will reach the various rewinding clutches 58 on the shafts 8, 9, 10 etc. successively, and practically one at a time, so that as all the main springs 42, 43, 44, etc. are tending to operate the rear central gear 55 as before explained, it is evident that as the latter revolves it can then wind up partially each successive spring, 42, 43, etc., without interfering with the steady operation of the main central shaft of the machine 26, since as each portion 47 is actuated in turn, the clutch 49 on the particular shaft being rewound frees the planetary gears 11, 12 etc. from the turning motion it otherwise would receive in an anti-clockwise direction. In order to give the springs 42, 43 etc. their initial winding to start the machine, it is necessary to either apply a crank 71 on the angular end of the part 60 of each planetary gear shaft individually, or when the mechanism is not too large and powerful, the whole rear central gear may be revolved by manual power using the handle located at 72 Figure 7, and in this way more quickly wind up the various actuating springs 42, 43, 44 etc.

From what has been said, it is believed the operation of device is readily understood, but will be briefly outlined. The springs 42, 43,

44 etc. are first completely wound up as just described. The actuating springs then tend to transmit motion through the clutches 49 on all of the planetary gear shafts 8, 9, 10 etc. to the planetary gears 11, 12, 13, etc. These in turn set in motion the rim gear 17, the idlers 19, 20, 21, and they in their turn set the front central gear 25 in motion. To prevent the mechanism moving at too great a speed, the brake shown and described in Figures 1, 4 and 5 is used, against the side face of the rim-gear as heretofore explained. The front central gear 25, actuates the central shaft 26, and turns the rear central gear 55 constantly. The latter is constantly in mesh with the rewinding gears 14, 15, 16 etc., and when the bossed portion of the ring 62 engages the groove of the part 61 of the clutch 58, on any particular planetary gear shaft, such as 8, for instance, the clutch is thrown into operation, the portion 47 of the shaft 8 is operated in an anti-clockwise direction, and the particular spring such as 42 in this instance is partially rewound, by the successive revolutions of the rear central gear 57. This procedure just described, of course applies to all the springs 43, 44 etc., and before the springs are completely "run down", it is evident that they have all been partially rewound many times, thereby extending the "running operation" of the original winding received to quite a long period.

It is apparent that the main central shaft 26 can be extended either at the front or rear of the machine, and the power obtained from the springs 42, 43, 44 etc. can be used in any suitable way for setting toys in operation, or where powerful springs are used power may be obtained for many purposes from the central shaft 26.

By way of illustration of one of the many uses of this mechanism, I have shown in Figures 9 and 10 of the drawings, the central shaft 26 belted to a "circular-saw". The shaft 26 is somewhat extended as stated above to permit the belt 73 to be mounted on it. A circular-saw 74 is revolvably mounted on the shaft 77, the latter being mounted in the saw-table 75 as shown. On the shaft 77 is also mounted the revolvable pulley 76, which is belted to the shaft 26 of the self-winding mechanism. It is evident that as the shaft 26 revolves the saw 74 will be operated to saw lumber placed on the table 75. The saw and table may be either of toy size, or they may be made of large size, sufficient for mill use, according to the size and strength of the driving mechanism which forms the subject of this invention.

60 I claim:

1. In a self-winding mechanism, a planetary gear shaft revolvably mounted in a series of supports, a planetary gear on the front end of said shaft, and a rewinding gear on the opposite end thereof, an actuating coil

spring, the inner end of which is secured to the planetary gear shaft, and its outer end attached to one of the vertical supports, a spring clutch for transmitting clockwise motion from the actuating spring to the planetary gear, a rear central gear and shaft revolvably mounted in the series of vertical supports, means for transmitting motion from the planetary gear to the rear central gear, a rear clutch in periodic engagement with the rewinding gear, for transmitting and converting clockwise motion of the rear central gear, by means of the rewinding gear, into anti-clockwise motion in the planetary gear shaft, for partially rewinding the actuating spring, and extending the operating period of the whole mechanism.

2. In a self-winding mechanism, a number of planetary gears and shafts revolvably mounted in a series of vertical supports, a number of actuating springs each mounted on one of the gear shafts, adapted to transmit clockwise motion to one of the planetary gears, a front central gear and shaft revolvably mounted in the vertical supports, a number of idler gears each mounted in a vertical support, and in engagement with the front central gear, a rim-gear having an outer set of teeth in engagement with the planetary gears, and an inner set of rim-teeth in engagement with the idler gears, a rear central gear on the rear end of the central shaft, a plurality of rewinding gears each freely mounted on one of the planetary gear shafts, and adapted to be revolved by the rear central gear in an anti-clockwise direction, means for periodically locking the rewinding gears on their respective shafts, for the purpose of partially rewinding the actuating springs of the mechanism successively, and extend the running period of the whole mechanism.

3. In a self-winding mechanism, a series of planetary gear shafts mounted in supports, an actuating spring means on each of the shafts, a rear central gear and shaft revolvably mounted in the supports, a rewinding gear on each of the planetary gear shafts, in meshed engagement with the rear central gear, motion transmitting means connecting the planetary gear shafts and the rear central gear, a bossed ring mounted on the latter gear, having a portion of its front face forming a bossed surface, an annular grooved casting on each of the planetary gear shafts, in engagement with the bossed ring, for periodically transmitting the motion of the rewinding gears to each of the planetary gear shafts in turn, as the bossed ring advances with the revolution of the rear central gear.

4. In a self-winding mechanism, a rear central gear revolvably mounted in supports, a number of planetary gear shafts revolvably carried in the supports, a plurality of loosely mounted rewinding gears, each mounted on one of the planetary gear shafts, and each of

- which is in meshed engagement with the rear central gear, a grooved annular casting rigidly and slidably mounted on the ends of each of the planetary gear shafts, a ring carried by the rear central gear, having a bossed portion on its rim face, adapted to slidably operate each of the grooved castings in turn along its shaft, and transfer the motion from each of the rewinding gears in turn to the planetary gear shafts, for the purpose of rewinding periodically the actuating springs, without interfering with the normal running action of the self-winding mechanism.
- 5 In a self-winding mechanism, a central gear shaft mounted in a series of supports, a front and a rear central gear, both rigidly mounted on the central gear shaft, a number of planetary gears each mounted on its shaft, carried in said supports, connecting means from the planetary gears to the front central gear, actuating spring means for the planetary gears, a plurality of loosely mounted rewinding gears, each on one of the planetary gear shafts, and each in engagement with the rear central gear, a grooved annular casting rigidly and slidably mounted on the ends of each of the planetary gear shafts, a ring carried by the rear central gear, having a bossed portion on its rim face, adapted to slidably operate each of the grooved castings in turn along its shaft, and transfer the motion from each of the rewinding gears in turn to the planetary gear shafts, for the purpose of rewinding periodically the actuating springs, without interfering with the normal running action of the self-winding mechanism.
